UNITED STATES PATENT OFFICE.

JOSEPH HENRY BLAIR, OF ST. LOUIS, MISSOURI, ASSIGNOR TO THE LODGE & SHIPLEY MACHINE TOOL COMPANY, OF CINCINNATI, OHIO, A CORPORATION.

TURRET ATTACHMENT FOR LATHE-CARRIAGES.

SPECIFICATION forming part of Letters Patent No. 766,488, dated August 2, 1904.

Application filed April 4, 1904. Serial No. 201,412. (No model.)

To all whom it may concern:

Be it known that I, JOSEPH HENRY BLAIR, a citizen of the United States, residing at St. Louis, State of Missouri, have invented certain new and useful Improvements in Turret Attachments for Lathe-Carriages, of which the following is a specification.

My invention relates to means for conveniently and rigidly mounting a tool-turret upon the carriage of an ordinary engine-lathe.

My invention also comprises an improved means for clamping the tools in the turret.

The features of my invention are more fully set forth in the description of the accompanying drawings, forming a part of this specification, in which—

Figure 1 is a top plan view of my device in position for use. Fig. 2 is a front elevation of the same, partly in section. Fig. 3 is a section on line *w w*, Fig. 1. Fig. 4 is an enlarged section on line *v v*, Fig. 1. Fig. 5 is an enlarged section on line *w w*, Fig. 4.

B represents the carriage, provided with the ordinary gibbed way C for the cross-feeding of the tool-post or tool-rest.

D represents the cross feed-screw.

E represents a plate bolted on top of the carriage and having its under surface fitted to the gib C of the carriage. Plate E is provided with a gibbed way F, to which the turret G is fitted. The turret has a depending lug H, through which the screw passes for reciprocating the turret. This lug depends through registering transverse slots formed in the transverse ways of the carriage and plate C F, respectively. This plate is a temporary attachment permitting a turret to be used on an engine-lathe in place of an ordinary tool-post. It affords the added strength and bearing-surface necessary in turret-work without interfering with the capacity of the tool for its ordinary work. It enables this machine to do work ordinarily requiring a different kind of machine. The plate can be readily

slipped on or off, bolted to position, and the 45 turret connected with the cross feed-screw. This plate is wider than the bridge of the carriage, and it forms a broad and rigid foundation for the turret, being securely bolted to the top of the carriage. This plate can be 50 readily constructed to fit upon the ordinary carriage and receive an ordinary turret. The carriage without this plate is not broad enough or rigid enough to support the turret.

For clamping the tool in the turret I provide a clamping-sleeve I, cut out at one side J to form a bearing for the tool K.

L represents a clamping-bolt passing through the sleeve I and having screw-threaded engagement with the turret. The sleeve 60 is provided with two bores a on each side of the bolt-bore into which springs b are inserted. When the bolt L is turned up to clamp the tool, the springs are compressed, and when the bolt L is loosened these springs 65 raise the clamping-sleeve I, releasing the tool.

Having described my invention, I claim—

A carriage for an engine-lathe provided with a slotted gibbed way for the ordinary tool-post, a cross feed-screw journaled in the 70 carriage, a plate the under surface of which is formed to fit the carriage gibbed way, the said plate being bolted to the carriage, the upper surface of the plate being formed with a transverse gibbed way provided with a slot 75 registering with the slot in the gibbed way of the carriage, and a turret formed to fit the gibbed way on the top of the plate and provided with a lug depending through the slots 80 in the carriage and plate and having screw-threaded connection with the cross feed-screw.

In testimony whereof I have hereunto set my hand.

JOSEPH HENRY BLAIR.
